PRESS BRAKE

Frederick E. Munschauer, Jr., Eggertsville, N.Y., assignor
to Niagara Machine & Tool Works, Buffalo, N.Y.

Filed Feb. 18, 1957, Ser. No. 44,889

Term of patent 14 years

(Cl. D63—1)

Fig. 2.

Fig. 1.

Fig. 3.

Fig. 1 is a perspective view of a press brake showing my new design taken from the front and top right front corner, thereof;

Fig. 2 is an enlarged side elevational view of the press brake; and

Fig. 3 is an enlarged front elevational view thereof. The major portion of the back of the article is open. I claim:

The ornamental design for a press brake, as shown and described.
